UNITED STATES PATENT OFFICE.

JOHN F. SHERBAHN, OF McCOOK, NEBRASKA.

BRICKKILN.

Application filed January 16, 1924. Serial No. 636,622.

To all whom it may concern:

Be it known that I, JOHN F. SHERBAHN, a citizen of the United States, residing at McCook, in the county of Redwillow and State of Nebraska, have invented certain new and useful Improvements in Brickkilns, of which the following is a specification.

This invention relates to brick kilns and has for its object the provision of a kiln which may be extended to any desired reasonable capacity without departing from the basic principles of its construction. Another object of the invention is to provide novel means for maintaining a draft through the kiln and utilizing said draft to carry off the products of combustion together with the obnoxious fumes which may be created during the process of burning the brick, and a further object of the invention is to provide a construction whereby the desired draft will be maintained with a stack of minimum height. Other objects of the invention will appear incidentally in the course of the following description, and the invention resides in certain novel features which will be hereinafter fully set forth and particularly defined.

In the accompanying drawings, which illustrate one embodiment of the invention, Figure 1 is a view, partly in plan and partly in horizontal section, of my improved brick kiln;

Fig. 2 is a view, partly in side elevation and partly in longitudinal vertical section, along the irregular line 2—2 of Fig. 1;

Fig. 3 is an enlarged detail view of one of the dampers;

Fig. 4 is a central longitudinal vertical section;

Fig. 5 is a transverse section on the line 5—5 of Fig. 4; and

Fig. 6 is a detail transverse section on the line 6—6 of Fig. 4.

A kiln constructed in accordance with my invention embodies a front wall 1, side walls 2 extending for any desired length according to the intended capacity of the kiln, and a back wall 3, the front and back walls connecting the side walls at the ends of the same, as will be readily understood upon reference to Fig. 1. These several walls are erected upon a foundation or substructure 4 which may be formed of concrete or brick or other suitable material, and the said substructure is of such form that it provides a central longitudinal flue 5 extending from

end to end of the kiln parallel with the side walls, and transverse walls 6 having flues 7 therein establishing communication between the said central flue 5 and chambers or short vertical flues 60 in the side walls, the floor of the kiln, indicated at 8, covering all of the said flues, and the vertical flues 60 having lateral openings 9 through the side walls to establish communication with the burning chamber. At intermediate points in the heights of the vertical flues, and preferably about at the level of the floor 8, rings or collars 10 are set in said flues, and a filling 11 of sand is placed around the said collars and supported by the laterally expanded annular bases 12 which carry the collars. The bases 12 may be built into the sides of the said flues 60 or otherwise supported fixedly therein. Above each collar 10, a damper 13 of an inverted cup form, shown most clearly in Fig. 3, is provided, the rim portion of this damper being of such diameter that it is adapted to fit around the collar 10 and embed its lower edge portion within the sand 11 so that, when the damper is lowered, the flue 60 will be closed and sealed. The damper is operated by a rod 14 extending upwardly through the side wall of the kiln and projecting above the top thereof, as shown in Fig. 2, a guiding and bearing plate 15 being provided at the top of the side wall for the damper rod, and a handle 16 being provided at the upper extremity of the rod. Doors 17 are provided in the side walls to permit the introduction of the brick to be burned and the removal of the burned brick, and these doors will, of course, be closed while the burning proceeds.

In the front wall 1, I provide a plurality of fireboxes 18, and the said front wall is so formed, as shown at 19, that openings or passages will be provided through which the heat from the several fire-boxes may pass into the kiln. By referring to Fig. 2, it will be noted that the fire-box comprises a grate 20 set in the front wall of the furnace and having an ash pit 21 below the grate, while the passages 22 formed in the said front wall establish direct communication between the several fire-boxes and the interior of the kiln. It will also be noted upon referring to Fig. 1 that the fire-boxes are disposed in a series extending entirely across the front wall with intervening partitions 23 so that, while the desired heat may be readily generated and carried into the burning chamber,

the wall will be strong enough to remain intact for a long period.

The return flue 5 opens through the rear wall 3 and the ground around the same is removed, as indicated at 24, so that access may be had to the flue whenever desired. A stack 25 is provided at some distance from the front wall of the kiln, and the flue 5 extends into the bottom of the stack, as 10 clearly shown in Fig. 2. In that side of the stack facing the front wall of the kiln, I provide a fire-box 26 including a grate 27 with an ash pit 28 below the grate.

In use, the bricks or other wares to be burned, indicated at 31, are piled within the kiln until they reach a level just below the top of the same, spaces being left at intervals, as indicated at 29 and 30, to define flues extending longitudinally through the 15 lower portion of the piled brick and vertically extending fire holes, respectively. Over all the piled ware, I place two flat layers of burned brick, 32, and these layers of flat brick are covered with sand, as indicated at 20 33, openings being left through the "flattening" or burned brick and sand to receive fire pots 34 closing the vertical fire holes at 25 their upper ends. The vertical fire holes and, of course, the fire pots are preferably 30 arranged at regular intervals forming transverse rows from end to end of the kiln. The rear wall 3 is hollow, having a chamber 35 therein which extends nearly to its 35 top and communicates with the interior of the kiln through openings 36 in the front side of the wall. The foundation or sub-structure includes a transverse flue 7 under the rear wall communicating with the chamber 35 through openings 37 in the floor 40 thereof, as shown in Figs. 4 and 6, short chambers 60 (described above) being provided at the ends of the chamber 35. While it is more economical to fill the kiln 45 for a burning, it is not necessary and the kiln may be fired when only partly filled. When the ware has been piled and covered as above described, the top of the kiln is air-tight and no heat can escape there-through, the draft being horizontal and 50 down. After a burning, the sand or dirt may be scraped off and stored on the walls of the kiln for use in the next burning. The burning is started at the front or furnace end of the kiln by building fires upon 55 the grates 20, all the dampers 13 being raised. The fire on the grates is maintained and increased for several days until the ware attains a white heat, the time required depending on the moisture content of 60 the green ware. When the ware attains a white heat, the fires upon the grates are permitted to gradually die out and firing is accomplished through the fire pots in the top. This top firing begins at the row of fire 65 pots next the front end of the kiln and right

above the grates, the dampers at and immediately in rear of said fire pots being closed. This row of fire pots is fired for five or six hours whereupon the second row is fired and succeeding rows in order until the eighth 70 row is reached, at which time the fires in the first row are allowed to die out. The firing is thus carried progressively through the length of the furnace, the dampers being closed in advance of the firing. When the 75 firing has been carried to the rear wall of the kiln, the chamber 35 and the openings leading into and from the same provide the draft necessary to complete the burning.

In the process of burning, the heavy moist 80 air is drawn off through the openings 9, the vertical flues 60 and the cross flues 7 into the main flue 5 so as to pass out through the stack. By kindling a fire in the fire-box 85 of the stack, a direct draft through the stack is established, and this draft creates a strong suction through the central flue 5 so that the moisture from the green bricks will be carried off effectually with a stack of less height than is now generally required.

Having thus described the invention, I claim:

1. The combination of a brick kiln having a fire-box in its front wall in direct communication with the interior of the kiln, a stack in spaced relation to the front wall of the kiln, a fire-box in said stack, and a return flue extending longitudinally under the floor of the kiln and establishing communication between the kiln and the base of the stack.

2. A brick kiln comprising side walls, a front wall and a back wall, a foundation upon which said walls are erected, a return flue extending longitudinally through the foundation and opening through the front and back ends of the foundation, transverse flues establishing communication between the said return flue and the burning chamber of the kiln, a fire-box at the front end of the kiln, a stack at the front end of the return flue, and a fire-box in said stack.

3. A brick kiln comprising a front wall, a back wall, end walls connecting the front and back walls, a foundation extending under all the walls and providing a floor for the entire kiln, a central return flue in said foundation, vertical flues in the lower portions of the side walls opening through the inner faces of the side walls into the interior of the kiln, transverse flues connecting the several vertical flues with the central return flue, dampers in said vertical flues whereby to control the circulation through the same, a fire-box at the front end of the kiln, a stack in direct communication with the front end of the return flue, and a fire-box in said stack.

4. A kiln having a fire-box in its front

wall, an escape flue extending longitudinally through the foundation of the kiln and open at both ends, and flues extending transversely through the foundation of the kiln to connect the interior of the kiln with the escape flue.

5. A kiln comprising a front wall, a back wall, and side walls connecting the front and back walls, a plurality of fire-boxes in

the front wall opening directly into the interior of the kiln, a longitudinally extending flue beneath the kiln, and means in the back wall and the side walls for establishing communication between the interior of the kiln and said flue. 10
